United States Patent Office.

JOHN SCHATZ, OF NEW HAVEN, CONNECTICUT.

Letters Patent No. 77,661, dated May 5, 1868.

IMPROVEMENT IN REED-ORGAN BELLows.

The Schedule referred to in these Letters Patent and making part of the same.

TO ALL WHOM IT MAY CONCERN:

Be it known that I, JOHN SCHATZ, of New Haven, in the county of New Haven, and State of Connecticut, have invented a new Improvement in Reed-Organ Bellows; and I do hereby declare the following, when taken in connection with the accompanying drawings, and the letters of reference marked thereon, to be a full, clear, and exact description of the same, and which said drawings constitute part of this specification, and represent, in—

Figure 1, an end view,

Figure 2 a top view, and in

Figure 3 a transverse section.

This invention relates to an improvement in that class of bellows such as are now commonly used in reed-instruments, and draw or suck the air through the reed, instead of forcing it, and the invention consists in the arrangement of collapsing-chambers in combination with the operating-bellows, so that the said chambers combined form a large chamber or reservoir, acting in connection with the bellows, so that the amount of power applied to drawing the air is very greatly increased, and thereby a more regular draught kept up, and enables the performer to operate the bellows regularly and steadily.

In order to the clear understanding of my invention, I will proceed to describe the same, as illustrated in the accompanying drawings.

A is the connection with the air-chamber, with which said air-chamber the reeds are in connection in the usual manner. Below the passage A is a fixed partition, B, and on the front, hinged at the top, is another partition, C, attached to the partition B by flexible enclosing-sides, D, and within the bellows a proper spring, E, is arranged, to support the partition C at the full extent of the flexible covering from the partition B. On the said partition C the two bellows F and G are arranged, as seen in fig. 3, so as to be operated by the treadles, each independent of the other, in the usual manner. Valves, d, on the bellows open as the bellows are depressed, to permit the exit of the air from the bellows; then, when drawn forward, a vacuum is formed in the bellows G, (by closing the valves d,) which vacuum is supplied from the chamber H, between the two partitions B and C, the air within the chamber passing through valves f into the bellows, thus exhausting the air from the chamber H. The partition C is depressed, the bellows again pressed forward, the air in the bellows passing out as before, and, so continuing, the air will be entirely exhausted, or nearly so, from both bellows, and the chamber H being in connection with the air-chamber through the passage A when the valves are open, the external air rushes through the valve and reed to supply the vacuum formed as aforesaid.

Thus far the arrangement is common and well known; and by this arrangement a difficulty occurs, in that when the air has been entirely exhausted in the chamber H and the bellows, the performer is obliged to rest upon the treadles, and the draught comes so strong at such times as to materially detract from the sound of the reeds, as the stronger the draught the stronger the sound; therefore great care is required by the performer in operating the bellows. To overcome this difficulty, and regulate more perfectly the operation, I arrange upon the back of the partition B two other chambers, I and K, similar in construction to the chamber H, as seen in fig. 3, the chamber I communicating through the passage A to the air-chamber in the same manner as the chamber H; and through the partition B, I form openings, i, covered upon the bellows-side by valves, h, and an opening, n, through the partition L, between the chambers I and K. By this construction, when the bellows is expanded, air is drawn alike from both chambers, I and H, through their respective valves, f and h, but when the bellows is fully expanded, then the two chambers, I and H, have been alike contracted, and the bellows is returned and the valves f and h closed. The opening between the chambers I and K is left free, and air passes through the opening from the chamber K until the three chambers, H, I, and K, are equalized; therefore the operator, keeping up a constant and steady blowing, the three chambers, equalized in the manner described, maintain a constant and steady draught from the air-chamber, and the "irregular blasts" often heard in the melodeon, as commonly constructed, are by this arrangement entirely avoided.

Having thus fully described my invention, what I claim as new and useful, and desire to secure by Letters Patent, is—

The arrangement of the two chambers I and K, or either of them, upon one side of a fixed partition, B, in combination with the chamber II and bellows F and G upon the other side of the said partition, and all of the said partitions connecting with the passage A, and constructed so as to operate together, in the manner and for the purpose herein set forth..

JOHN SCHATZ.
